Filed Aug. 4, 1965, Ser. No. 86,433

Term of patent 14 years

(Cl. D52—2)

FIG. -2-

FIG. -1-

FIG. -4-

FIG. -5-

FIG. 1 is a front elevational view of a combined tissue and towel dispenser embodying my new design.

FIG. 2 is a top plan view of FIG. 1.

FIG. 3 is a bottom plan view of FIG. 1.

FIG. 4 is a side elevational view showing the dispenser in one position thereof.

FIG. 5 is similar to FIG. 4 showing the dispenser in another position thereof.

The undisclosed side of the dispenser is a mirror image of the side shown, and the rear is substantially plain in appearance.

I claim:

The ornamental design for a combined tissue and towel dispenser, as shown and described.
